A. B. Upsham,
Attorney.

UNITED STATES PATENT OFFICE.

OMER A. CONTE, OF NEEDHAM, MASSACHUSETTS.

STOP-MOTION FOR WINDING-MACHINES.

1,364,354.

Specification of Letters Patent.

Patented Jan. 4, 1921.

Application filed January 15, 1920. Serial No. 351,960.

To all whom it may concern:

Be it known that I, OMER A. CONTE, a citizen of the United States, and a resident of Needham, in the county of Norfolk and

5 Commonwealth of Massachusetts, have invented certain new and useful Improvements in Stop-Motion for Winding-Machines, of which the following is a full, clear, and exact specification.

10 In machines for winding thread upon cones it frequently happens that the thread gets beyond the large end of the cone and becomes wound upon the actuating spindle, thereby entailing loss of time in untangling 15 the snarl, as well as of valuable material.

The object of this invention is the construction of an attachment to a well known type of cone winder, by means of which the machine will be automatically stopped as 20 soon as the thread begins to get beyond the end of the cone.

Referring to the drawings forming part of this specification, Figure 1 is a perspective view of parts of a well known form of 25 cone winder showing my attachment applied thereto. Fig. 2 is an elevation of parts of the same. Fig. 3 is a plan view of a plate carrying certain operative portions of my attachment.

30 The parts indicated in the drawings as those of a well known form of winding machine, comprise portions of the frame 1, the traverse frame 2 oscillative on an axis concentric with the stopping lever wheel 3, the frame 2 having a counterweight 4.

35 Pivotally supported on the traverse frame dog segment 5 is the stopping lever 6 whose extremity 7 is normally supported close to the periphery of the stopping lever wheel.

40 3. The normal support is the yarn being fed to the cone 9, and the operation is such that when the yarn breaks, the lever extremity swings against the periphery of the wheel 3 and the cogs 10 thereof strike

45 the lever extremity 7 with such force as to communicate an upward throw to the segment 5, and thereby to unclutch the cone from the driving mechanism, and at the same time to apply a braking action to the 50 rotation of the cone in the well known manner in which these machines are constructed.

55 My attachment to this winding machine comprises a lever 11 pivotally supported at 12 to swing both axially and radially with respect to the cone 9. The pivotal support shown in Fig. 2 is more clear in construction

than that illustrated in Fig. 1, the helical spring 13 acting to press the upper end of the lever against the large end of the winding cone 9. Connected with the lever 11 by a 60 tubular bar 14 is the nose 15 of a latch 16 designed for holding a bar 17 normally in an outward position, a helical spring 19 serving to draw this bar 17 inward. The outer end of the bar 17 is connected by a wire 65 arm 20 having a horizontal elbow 21 terminating in a hand 22 disposed to engage the section 23 of the stopping lever 6.

When the latch 16 is pressed back by a lateral push given to the lever 11, the bar 70 17 is released and springs inward, thereby giving a corresponding push to the stopping lever 6, the bar acting through the arm 20. This action on the stopping lever puts it into engagement with the cogs 10 and thereby 75 stops the actuation of the cone 9 in the manner already referred to.

A light spring 25 in the housing 24 serves to keep the latch 16 in secure normal control of the bar 17, and the nose 15 is tapered to 80 permit the tubular connector 14 to oscillate with the lever 11 as the latter is given a swing in a radial direction relative to the cone. This radial swing has for its object to permit the lever to be withdrawn from 85 the cone when the traverse frame 2 is moved away from the cone. To perform this automatically, I connect the frame 2 with the lever 11 by a wire 26, by means of which 90 the lever will swing away from engagement with the cone simultaneously with the traverse frame.

By means of this attachment, if the yarn should begin to wind upon the cone-mandrel beyond the designated base of the cone, the 95 yarn would press against the lever 11 and thereby release the bar 17 and stop further winding until the yarn is properly placed, and the bar 17 reset.

As shown in the drawings, this attachment can be readily applied to an existing winding machine of the type specified.

What I claim is:

1. The combination with a winding machine having an automatic stop motion, of 105 a member yieldingly pressed in an axial direction against an end of the material being wound, and means connected with said automatic stop whereby an axial displacement of said member will actuate said automatic stop.

2. The combination with a winding ma-

chine having an automatic stopping device, of a member yieldingly pressed in an axial direction against an end of the material being wound, a latch connected with said member, and a spring-actuated device connected with said stopping device for operating it normally held inactive by said latch, the latter being adapted to release said spring-actuated device when said member is dis-
10 placed.

3. The combination with a winding ma-
chine having an automatic stopping device,
of a pivotally supported lever disposed for
resting against the end of the material be-
ing wound, and means connected with said
stopping device and controlled by said lever
whereby the displacement of said lever actu-
ates said stopping device.

4. The combination with a winding de-
vice having an oscillating traverse frame
and an automatic stopping device, of a pivotally
supported lever disposed for resting
against the end of the material being wound,

means connected with said stopping device
and controlled by said lever whereby the 25
displacement of said lever actuates said
stopping device, and a connection between
said frame and lever whereby the two swing
in unison to and from the work.

5. The combination with a winding de- 30
vice having an automatic stopping device
and supporting means, of a plate held by
said supporting means, a bar slidably sup-
ported by said plate, a latch carried by said
plate for holding said bar in a set position, 35
a spring acting on said bar, a member rest-
ing in contact with an end of the material
being wound, and connection between said
member and latch whereby the displacement
of said member causes the latch to release 40
said bar and the stopping device to be ac-
tuated.

In testimony that I claim the foregoing
invention, I have hereunto set my hand this
14th day of January, 1920.

OMER A. CONTE.
